FINGER RING

Nat Levy, New York, N. Y.

Application June 19, 1937, Serial No. 149,075

1 Claim. (Cl. 63—15)

The invention here disclosed relates to finger rings.

The objects of the invention are to provide a novelty ring for holding a handkerchief, scarf 5 or the like, or which if desired, may be utilized to carry perfume and to provide such a structure in a simple, inexpensive but practical, durable and attractive, desirable form.

These and other desirable objects are attained 10 in this invention by the novel features of construction, combinations and relations of parts, hereinafter described and broadly claimed.

The drawing accompanying and forming part 15 of the specification illustrates one practical commercial embodiment of the invention, it being understood that the structure may be modified, all within the true and intended scope of the claim.

Fig. 1 is a perspective view illustrating the 20 use of the invention for carrying a lady's handkerchief.

Fig. 2 is an enlarged side view of the invention.

Fig. 3 is a cross-sectional view as on substantially the plane of line 3—3 of Fig. 2.

The body of the ring is shown as made of a 25 band of sheet metal 5, having a widened base or head portion 6, and the ends overlapped for sizing adjustment at 7. At one edge, the base is shown as extended outwardly away from the ring 30 in the form of a lug 8, having hinge studs 9, at opposite edges and a rounded end edge 10, to form a cam.

Secured over the base is a shallow box 11, having a flanged rim 12, cut away at 13, in line 35 with and to expose the cam lug 8. This flanged rim is shown as serrated at 14, for the purpose of gripping a handkerchief, scarf or other such article.

A hollow ornamental cover element is shown 40 at 15, having a flat perforated ornamental disc 16, within it for clamping cooperation with the serrated rim of the box member.

A hinge strap is shown at 17, secured to the 45 inside disc 16, having angularly bent lugs 18, pivotally engaged over the hinge studs 9.

For yieldingly retaining the cover in the closed clamping relation indicated in Fig. 1, or in the partly open relation, Fig. 3, a bowed flat spring is shown at 19, having notched ends 20, caught over the hinge lugs 18. Secured in this relation, 5 the bowed spring is in position to ride over the curved edge of the holding cam 8, to snap the cover and to yieldingly retain it either in the open or closed relation. Fig. 3 shows how in passing from one position to the other, the bowed 10 spring is flattened out to store energy for snapping the cover one way or the other.

Suitable ornamental elements such as indicated at 21, may be secured at the sides of the ring over the spaces between the band and box 15 portions, in position to conceal the joint between these parts and producing the effect of a merger of the band into the widened box portion.

In Fig. 1, the ring is shown in use for holding 20 a handkerchief. The spring and cam combination causes the cover element to clamp the material of the handkerchief or other article with a desirably firm but non-injurious pressure. The serrated rim of the box provides a sufficiently 25 long gripping edge to prevent injury to delicate fabric. If desired, perfume may be carried on a pad seated in the box, or such a pad may be located in the dome of the cover behind the perforated plate 16 and used for perfuming any 30 handkerchief or other article that may be held in the ring. The box structure may be used either as a container or, in conjunction with the cover as a clamp, or if desired, may simultaneously be used for both these purposes. 35

What is claimed is:

A finger ring, comprising a band provided with an angular extension, a box secured on said band and having a serrated flange interrupted to expose said extension, a cover hinged to said extension and positioned thereby for clamping engagement with said serrated flange and spring means on said cover for yielding engagement with said extension. 40
